Patented July 4, 1922.

UNITED STATES PATENT OFFICE.

OTHMAR SEEBERGER, OF BRUGG, SWITZERLAND.

BOBBINET-MAKING MACHINE.

1,421,579.

Specification of Letters Patent.

Patented July 4, 1922.

Application filed April 13, 1921. Serial No. 460,884.

To all whom it may concern:

Be it known that I, OTHMAR SEEBERGER, citizen of Switzerland, residing at Brugg, Canton of Aargau, Switzerland, have invented certain new and useful Improvements in Bobbinet-Making Machines, of which the following is a specification.

This invention has for its object to provide an improved bobbinet making machine with closed race or track.

Machines of this kind are already known. All of them have, however, the drawback that, for the purpose of producing the initial movement of the bobbin when the latter changes its place, a considerable amount of power must be transmitted for this purpose through the pattern mechanism. This results in irregularities in, and even stoppages of, the work.

In particular, this places a great strain upon the pattern cards which have to be renewed very frequently.

Further the constructions hitherto known have the further disadvantage that at the beginning and at the end of their change of place the bobbins have to be pushed into, and moved out of the race or track by special devices. In this matter the feet of the bobbins are frequently jammed, or they knock against one another as a result of inaccurate adjustment of the actuating parts, thus entailing many repairs, and thereby causing the machine to remain idle for an excessive length of time.

Such interruptions are rendered impossible by the present invention whereby the pattern mechanism is not required to impart motion to the bobbins, and therefore no devices are necessary for inserting the bobbins into the race or track.

The movement of the bobbins is effected by discs which run selectively and which, in their turn, are coupled directly to the driving wheels that are mounted underneath, and are automatically uncoupled again therefrom after a partial revolution.

A constructional example of this invention is illustrated by way of example in the accompanying drawings in which—

Fig. 1 is an elevation, and

Fig. 2 is a view of the raceway when arranged in a straight line.

Fig. 3 is a section through a bobbin stem.

Fig. 4 is a side elevation of an under-part of a disc, and

55

Fig. 5 is a plan of a bar.

The exact shape of the disc is shown in Fig. 6 which is a partial plan.

As shown in Fig. 3, the driving wheel *a* rotates around the stationary stem *b*. In 60 the extended hub of the driving wheel *a* there is mounted in an axially slidable manner a clutch pin *c*, which is parallel to the axis of the driving wheel *a* and around which is arranged a coiled spring *d*. This spring *d* 65 bears at one end against the wheel *a* and at its other end against a pin *e* that extends transversely through the aforesaid clutch pin *c*. Below the pin *e* is a second pin *f* which extends parallel to the pin *e* through 70 the clutch pin *c*. In the hub of the driving wheel there is further mounted in a radially slidable manner a bar *g*. The outer end of this bar is formed with a truncated double bevel as shown in Fig. 5.

75

The double beveled bar *g* is formed at its upper end with a groove *h*. In an inwardly extending recess in the bar *g* there is arranged a spring *i* which has a tendency to push the said bar outwards.

80

The clutch pin *c* extends freely through a transverse slot *g*¹ of the bar *g* in such a manner as not to hinder the radial movement of the said bar *g*. The bar *g* is held in its inner locking position by the engagement of the ends of the pin *f* in recesses *g*² of the bar *g*.

85

k is a nib provided on the hub of the wheel diametrically opposite the bar *g*.

m are the discs which are situated in the 90 upper plate *l* and which are adapted to rotate freely around their stems *b*.

The height of the discs *m* is exactly equal to the thickness of the top plate *l*. The discs *m* may have the same diameter throughout 95 their entire height, or they may be so formed and arranged that each pair of adjacent discs will engage in or over one another by means of their projecting edges.

Each disc *m* has further two diametrically 100 opposite recesses *n* (Fig. 6) which are so shaped as to be adapted to determine the path of the bobbin *O*, and so that the noses *x*, formed by the recesses *n* in the discs are caused to act as drivers for the bobbins.

105

Below the disc *m* and fixed to it, is a

flange p formed with two diametrically opposite radially extending lugs q shown in side elevation in Fig. 4.

In the flange p there is formed a small 5 depression r into which, for the purpose of accurately stopping the disc m , a nib provided on a spring s , is caused to snap by the pressure of a spring s .

In the lower disc there is arranged a pin 10 v which is guided by means of a sleeve u , and which can be raised and lowered in the usual manner by means of a pattern mechanism, whereby the said pin imparts its movements to the ring w , that is fixed on the pin 15 v . The manner of operation is as follows:—

If for instance the bobbins O^1 and O^2 (Fig. 1 and 2) are to change over so that O^1 moves over to O^2 , and O^2 moves over to O^1 , the pin v^2 and with it the ring w^2 will 20 be raised by the pattern mechanism in the usual manner.

The ring w^2 presses the rod c^2 upwards, and since the wheels a are continuously rotating around the stems b , the rod c^2 , situated on the wheel a^2 , will in its raised position (indicated in dotted lines in Fig. 3) transmit, by pressure upon one of the lugs q , rotary motion to the disc n^2 .

In the rotation of the disc, the noses x, x , 30 carry the bobbins O^1 and O^2 round with them.

In order, however, that the rotary motion of the discs shall be accurately limited, the further above described means are provided.

In raising the rod c^2 and with it the pin e , the spring d is stressed, and as soon as the clutch pin e has been raised to such a height that the pin f has come level with the groove h , the pressure of the spring i will cause the 40 bar g to shoot outwards, so that the pin f bears against the bottom of the groove h , and the clutch pin e can not move down.

So long as this position continues, the coupling between the wheel a^2 and the disc 45 m is maintained, and the disc m will revolve with the wheel a^2 . After almost one completed half revolution, the bar g will strike the nib k of the adjacent driving wheel, and will be forced back by the said nib, whereby 50 the spring i is stressed again.

At the same time, the pin f loses its bearing upon the bottom of the groove h , and the clutch pin e^2 is caused, by the pressure of the spring d , to drop back into its position 55 of rest. By this means the pressure upon the lug g ceases, and the disc ceases to rotate. In order that the rotation of the disc shall cease exactly at the proper moment, the nib situated on the spring s snaps into the corresponding recess r of the flange p and thus holds the flange p and through it the disc m fast.

During the half revolution the bobbins 60 O^1 and O^2 have changed places, and the bobbins remain, midway between every two ad-

jacent discs; that is to say, they are not moved out of the race or track as hitherto. Consequently no devices of any kind are necessary in order to move the bobbins back into the race or track, and therefore the 70 strain on the pattern mechanism which is required for this purpose in other bobbinet making machines, is absent, thus allowing of a considerable saving in wear and tear of the said mechanism.

What I claim is:—

1. A bobbinet making machine of the kind described, comprising a stationary stem, a drive wheel rotatably mounted on said stationary stem, a clutch pin axially slid able in the drive wheel and turning with the same, a pattern mechanism to control the upward movement of the clutch pin, a spring to control the downward movement of the clutch pin, a spring pressed bar radially slid able in the drive wheel and capable of locking the clutch pin in the raised position and of being locked in the inner position by the clutch pin, a projection provided on the drive wheel diametrically opposite the bar, a disc adapted to rotate freely around the said stem and having recesses forming noses to drive the bobbins and having also two diametrically opposite radially extending lugs capable of being engaged by the clutch pin and means for accurately and yieldingly stopping the disc.

2. A bobbinet making machine, comprising a stationary stem, a drive wheel rotatably mounted on said stationary stem, a clutch pin axially slid able in the drive wheel and turning with the same, a pattern mechanism to control the upward movement of the clutch pin, a spring to control the downward movement of the clutch pin, a spring pressed bar radially slid able in the drive wheel and having a transverse slot to receive the clutch pin, a horizontal groove to support a part of the clutch pin in its raised position, vertical recesses to receive the said part of the clutch pin and a double beveled outer end, a projection provided on the drive wheel diametrically opposite the bar, a disc adapted to rotate freely around the said stem and having recesses forming noses to drive the bobbins and having also two diametrically opposite radially extending lugs capable of being engaged by the clutch pin and means for accurately and yieldingly stopping the disc.

3. A bobbinet making machine of the kind described, comprising a stationary stem, a drive wheel rotatably mounted on said stationary stem, a clutch pin axially slid able in the drive wheel and turning with the same, a pattern mechanism to control the upward movement of the clutch pin, a spring to control the downward movement of the clutch pin, a spring pressed bar radially slid able in the drive wheel and capable of locking the

clutch pin in the raised position and of being locked in the inner position by the clutch pin, a projection provided on the drive wheel diametrically opposite the bar, a disc 5 adapted to rotate freely around the said stem and carrying a flange having recesses forming noses to drive the bobbins and also two diametrically opposite radially extending lugs capable of being engaged by the

clutch pin and a spring coacting with a depression in the said flange to accurately and yieldingly stop the disc.

In testimony whereof I have affixed my signature in the presence of two witnesses.

OTHMAR SEEBERGER.
